(57) **CLAIM**

The ornamental design for a headboard/footboard for an adjustable bed, as shown and described.

DESCRIPTION

FIG. 1 is a front perspective view of a headboard/footboard for an adjustable bed, showing my new design;

FIG. 2 is a front view of the footboard and rear of the headboard;

FIG. 3 is a front view of the headboard and rear of the footboard;

FIG. 4 is a top plan view thereof;

FIG. 5 is a side elevation view thereof;

FIG. 6 is a side opposite that shown in FIG. 5;

FIG. 7 is a bottom plan view thereof;

FIG. 8 is a rear perspective view of the headboard/footboard for an adjustable bed;

FIG. 9 is a rear elevation view thereof;

FIG. 10 is a front elevational view thereof;

FIG. 11 is a front perspective view showing the design in an alternative environment;

FIG. 12 is a rear perspective view showing the design in an alternate environment;

FIG. 13 is a rear elevational view thereof; and,

FIG. 14 is a front elevational view thereof.

FIGS. 2-7 show the headboard/footboard separately for convenience of illustration.
